Primary Examiner — Derrick Holland*Assistant Examiner* — Janice Lim(74) Attorney, Agent, or Firm — Michael L. Greenberg, Esq.; Greenberg & Lieberman, LLC(57) CLAIM

The ornamental design for a jewelled heel, as shown and described.

DESCRIPTION

FIG. 1 is a left rear perspective view of a jewelled heel, showing my new design;

FIG. 2 is a right rear perspective view thereof;

FIG. 3 is a top plan view thereof;

FIG. 4 is a bottom plan view thereof;

FIG. 5 is a right side view thereof;

FIG. 6 is a left side view thereof;

FIG. 7 is a front view thereof; and,

FIG. 8 is a rear view thereof.

The broken line portions of FIGS. 1-8 are included to show unclaimed subject matter only and form no part of the claimed design.
